UNITED STATES PATENT OFFICE.

JACOB FELBEL, OF NEW YORK, N. Y., ASSIGNOR TO UNION TYPEWRITER COMPANY, OF JERSEY CITY, NEW JERSEY, A CORPORATION OF NEW JERSEY.

TYPE-WRITING MACHINE.

SPECIFICATION forming part of Letters Patent No. 788,763, dated May 2, 1905.

Application filed June 23, 1903. Serial No. 162,774.

To all whom it may concern:

Be it known that I, JACOB FELBEL, a citizen of the United States, and a resident of the borough of Manhattan, city of New York, in the county of New York and State of New York, have invented certain new and useful Improvements in Type-Writing Machines, of which the following is a specification.

This invention relates to improvements in the type-actions and carriage-feed mechanism of front-strike type-writing machines which comprise pivoted type-bars and mechanism to swing them on their pivots upward and backward to their printing positions, in which they act on the paper on the front of the platen, and usually on or near the line on which the horizontal plane that contains the axis of the platen cuts the paper, the object of the invention being to provide such machines with highly efficient type-actions composed of simple and easily-assembled parts and having various peculiar and desirable characteristics, which will be hereinafter explained, and with carriage-feed mechanism fitted to be suitably actuated by the type-actions and to coact therewith in accurately controlling the feed movements of the carriage and in regularly securing a feed movement whenever any type-bar receding from its printing position has traveled a certain distance from the platen.

The invention consists of the various features of construction and combinations and arrangements of parts, all as hereinafter more fully described, and particularly defined in the appended claims.

In the accompanying drawings, in which like reference-numerals designate like parts in different views, Figure 1 is a central vertical section through the front and back of the frame of a front-strike type-writing machine with mechanism embodying certain parts of the invention applied thereto and an outline of the platen; Fig. 2, a plan of the universal bar of the carriage-feed mechanism and horizontal section of levers included in the type-actions; Fig. 3, a front view of the universal bar; Fig. 4, a fragment of the frame and a clamp attached thereto in perspective; Fig. 5, a front sectional elevation, on an enlarged scale, of

the mechanism shown behind the planes xx , 50 Fig. 1, with other type-actions added; Fig. 6, a diagrammatic plan of connecting-links extending from the key-actuated devices shown in Fig. 1 to the lower ends of the straight levers shown in Fig. 5, two of these connecting-links and two of the levers being also shown in Fig. 1; Fig. 7, a front sectional elevation, on the same scale as that of Fig. 5, of the frame, type-bars, and a modification of the system of straight levers shown in Fig. 4, the modification differing with respect to the relative positions of the levers on their pivotal axis and the forms of their upper arms from the system of straight levers; and Fig. 8, a diagrammatic plan of connecting-links extending from key-actuated devices like those shown in Fig. 1 in the front portion of the base to the lower ends of the levers of the modified system.

The invention is shown applied to a machine all parts of which except the type-actions and carriage-feed mechanism are devoid of material novelty. In the frame of this machine, composed of the base 1, posts 2, fast on the base, and top plate 3, fast on the posts, are fixed guide-blocks 4. These guide-blocks are formed on or attached to the sides of the base 1 and are a little forward of a vertical plane passed in front of the platen 5. A type-bar segment 6 is slidably secured between these guide-blocks, there being brackets 7 on the ends of the segment proper, and in grooves in these brackets and in the guide-blocks are antifriction-balls 8. These parts are so adjusted that the segment is easily movable up and down, but cannot swerve laterally in the guides. The segment 6 contains a series of radial grooves 9, cut in its hollow face, the number of these grooves being equal to the number of type-bars, and within a groove 90 crossing the grooves 9 at right angles and extending from end to end of the segment is a curved pivot-rod 10. The type-bars 11 are pivoted in the grooves 9 on the rod 10, there being a type-bar in each of the grooves 9. On the pivoted end of each type-bar is a short arm 12, in which is a hole 13 for connection of an actuating-link. When the type-bars

are in their normal positions, they extend forward from the segment 6 and rest near their front ends on a segment 14, which is secured to the segment 6 by bars 15 and provided with 5 a pad 16, of soft material—such, for example, as felt.

Behind the plane containing the rear faces of the guide-blocks 4 and segment 6 are brackets or hangers 17, which are affixed at their upper ends to the top plate 3 of the frame and connected at their lower ends by a cross-bar 18. This cross-bar contains a series of vertical slots 19, extending through the bar from top to bottom and from its rear face inward a suitable distance, as appears at Fig. 1. A system of levers is mounted on a horizontal rod 20, fixed in this cross-bar and extending from end to end of the bar across the slots 19, there being a lever in each of the slots. The levers are preferably straight, as shown in Figs. 1 and 4. When the system is composed of the straight levers 21, the distance between the hangers 17 is less than the span of the segment 6, and the slots 19 in the cross-bar 18 are so arranged that planes passing through these slots midway between and parallel to their faces cut the holes 13 in the arms 12 of the type-bars. The straight levers 21 extend upward from their pivot-rod 20 behind the arms 12 of the type-bars and are connected therewith by links 22, the upper ends of the levers conforming to an arc whose radius is a little shorter than that of the segment 6. The length of the lower arm of each of these levers is equal to that of its upper arm, so the lower ends of the levers also conform to an arc similar to that at their upper ends, and these arcs diverge from each other from the middle to the sides of the system.

In the front portion of the base 1 four parallel cross-rods 23 are secured. These rods are supported at their ends by the sides of the base, each rod being held fast by a clamp at one end or each end of the rod. The construction and operation of one of these clamps is clearly illustrated at Fig. 4. It is composed of a block 24, containing a recess 25, in which is a movable jaw 26 on the lower end of a screw 27, the block being affixed to a side of the base 1. The screw fits in a threaded hole in the arm 28 of the clamp, and the fixed jaw 29 has in its upper face a groove in which is shown a section of a rod 23, secured between the fixed and movable jaws. The cross-rods 23 support key-actuated levers having arms 30 and 31, which extend backward and upward and backward and downward, respectively, from the cross-rods when the levers are in their normal positions. To the arms 30 of these levers are pivoted the stems 32 of finger-keys 33, and to the arms 31 are attached restoring-springs 34, which are also attached to transverse cross-bars 35, fastened to the base of the frame. The stems 32 extend through transverse guide-plates 36,

which are fastened at their ends to the frame and which, with the arms 30 of the levers, maintain the stems 32 and finger-keys 33 in their proper positions. The space-bar 37 is mounted on levers on the front cross-rod 23, 70 which are not shown, but which are similar to the levers to which the finger-keys 33 are secured. All the levers on the cross-rods 23 have eyes or bearings 38, and the cross-rods extend through these eyes. 75

The key-levers described are connected by links 39 with the lower arms of the levers 21, these link being secured at their front ends to the arms 31 of the key-levers and extending thence backward to the levers 21 under the type-bars. Since the system of key-levers is broader than the system of straight sublevers 21, the system of connecting-links 39 is broader at the front than at the rear ends of the links, or, in other words, the links converge slightly from their front to their rear ends, as appears at Fig. 6. With the depression of a finger-key 33 the key-lever connected therewith is actuated, the lower arm 31 of the key-lever being swung toward the front of the machine, so that the link 39, connecting the key-lever with one of the sublevers 21, is drawn forward and the lower arm of the sublever is pulled forward by the link. Meanwhile the upper arm of the sublever pulls the link 22 backward, and the type-bar is thus swung from its normal to its printing position by the action of the link 22 on the arm 12 of the type-bar. A spring 40, attached to the type-bar and to an arm 41 affixed to the segment 14, helps to restore the type-bar to its normal position. It will be observed that in the operation of this system of type-actions several of the central type-actions of the system are not subjected to any or to any but very slight lateral or twisting strains and that even the other type-actions are not much affected by any such strains, although the links 39 converge from their front to their rear ends, because the inclination of any link to a vertical plane cutting at right angles the axes of the pivot-rod 20 and cross-rods 23 is so small and each link 39 is so long that the minute lateral strains exerted on the key-lever and sublever connected by any link absorb but a very small per cent. of the force applied to the finger-key.

The modified system of sublevers shown in Fig. 7 is composed of levers 42, whose ends conform to arcs which diverge from each other from the middle to the sides of the system. The width of this system at the bottom and at and above the pivotal axis of the levers is equal to that of the system of key-levers, and these sublevers are so arranged that the lower end of each sublever is between vertical planes containing the lateral faces of one of the key-levers. In other words, the lower end portion of each sublever is in the same vertical plane as the arm 31 of the associated key-lever. 120 125 130

ver, so that a direct fore-and-aft pull will be exerted from an arm 31 to its associated sublever. These sublevers are connected with the key-levers by links 43, similar to the links 39; but the links 43 are parallel instead of inclined to a vertical plane cutting at right angles the axes of the pivot-rod 20 and cross-rods 23. This modified system of sublevers is supported by brackets or hangers 44, a slotted cross-bar 45, and a pivot-rod extending from end to end of the cross-bar through the slots therein, this pivot-rod being like the rod 20, except that it is longer. The hangers 44 are similar to the hangers 17, but are farther apart than are the others. They are also affixed to the top plate 3 of the frame, from which they extend downward behind the guide-blocks 4 and brackets 7 of the segment 6. The cross-bar 45 is like the cross-bar 18, except that it is longer and that the slots in which the sublevers are secured are farther apart than are the slots in the other bar. The levers of this system, except the two nearest to the middle of it, are bent inward above the cross-bar 45, as shown by Fig. 7, the upper ends of these levers being in the same positions with relation to the type-bars as are the upper ends of the straight levers 21 of the other system and the radius of the arc at the upper ends of the levers 42 being naturally shorter than that of the arc at their lower ends. The upper and lower ends of each lever 42 are equally distant from a horizontal plane containing the axis of the common pivot-rod of the levers. These levers are connected with the type-bars by links 22, pivoted at their rear ends to the upper arms of the levers and at their front ends to the arms 12 of the type-bars. The action of these sublevers will be understood from the foregoing description of that of the sublevers 21. As the lower end of one of them is pulled forward by a link 43 its upper end is carried backward and the type-bar is swung to its printing position by the link which connects the sublever with the type-bar. Only small lateral or twisting strains are exerted on any of the sublevers of this modified system, although, with the exception of the straight levers at the middle 50 of the system, all are slightly subject to such strains in consequence of the bends in the upper arms of the levers.

The sublevers of each system above described are so arranged that the ends of all 55 the levers swing from side to side of the vertical plane containing their common axis and are equally distant from that plane when the type-bars are in their normal positions and when they are in their printing positions. 60 The movements of the longest levers, or those at the sides of the system, are consequently measured by the smallest angles, and the movements of the other levers in order from either of the side levers to the middle levers of the 65 system are measured by progressively-increas-

ing angles, while the ends of every lever are movable through greater distances toward and from the front of the machine than they are toward and from the top of the machine. Since then the ends of each lever move through 70 equal distances or since its arms are subjected to equal strains, it is expedient to make the arms of each straight lever symmetrical, as they are shown in the system illustrated in Figs. 1 and 5. In securing these levers in 75 the cross-bar 18 it is unnecessary, therefore, to exercise care concerning which ends of any lever are made its upper and lower ends, respectively. Moreover, since the lower ends of all the sublevers of either system move 80 through substantially equal distances the connections between the sublevers and finger-keys have movements that are almost equal, and naturally under these conditions the depressions of the finger-keys are substantially equal. 85 The arms of each sublever preferably extend from its pivotal axis in diametrically opposite directions, and the sublevers of each system are preferably arranged as described with relation to the vertical plane containing their 90 common pivotal axis; but obviously sublevers differing to a considerable extent in form and arrangement from the levers 21 or 42 might be embodied in lieu of these levers in mechanism containing, essentially, the invention. 95 It will be observed that each of the sublevers shown has its ends on opposite sides of a plane which contains the pivotal axis of the sublever and forms right angles with one of the arms of the sublever. A plane containing the pivotal axis and forming right angles with one of the arms of a lever is understood to be a plane containing said axis and forming right angles with another plane also containing said axis and cutting the arm of the lever at the point where either the power or weight acts on the lever. The ends of a lever are understood to be where the power and weight act on the lever. 100 The carriage-feed mechanism comprises a 105 universal bar which is operative by the sublevers to regulate the feed movements of the carriage. The bar 46 extends across the frame a little behind and above the common axis of the sublevers, being supported at its ends by horizontal guides. These guides are 110 composed of devices 47, affixed to the base, and of pins 48, fast on the bar and fitting in the devices 47, as appears by Fig. 2, the pins being movable freely back and forth in the eyes of the devices 47. To this bar midway between its ends is attached a rod 49, which extends backward from the bar to and through an arm 50 on the rock-shaft 51 of a dog-rocker 52, there being on the rod 49 a nut 53 to bear against the arm 50 and a lock-nut 54. The dog-rocker carries feed-dogs 55 and 56, which act on the escapement-wheel 56^a of the feed mechanism, and on the shaft 51 is a restoring-spring 57. The dog-rocker, arm 50, rod 49, and universal bar 46 are normally 115 120 125 130

held by the spring 57 in the positions shown in Fig. 1. That portion of the front edge or face of the universal bar which is directly behind the sublevers and on which they act is composed of surfaces 58, intersecting each other at 59 and there forming an obtuse angle not much smaller than two right angles, as appears by Figs. 2 and 3, the shape of the face being such that it fits against the backs of all the sublevers from side to side of the system when the levers are in their normal positions, whereas if the face were straight from end to end it would touch only the two side levers. Consequently each sublever acts in the same time on the universal bar and forces it backward when the sublever is actuated by depressing its finger-key. Moreover, the bar is bent at 59, as appears by Fig. 3, so that it makes contact with the sublevers at different distances from the horizontal plane containing their common axis. These distances, which progressively increase from the middle to the sides of the system, are such that the bar is subjected to contact with those portions of the sublevers by which it is movable through a certain distance, so that whatever sublever is actuated the bar is moved to the same extent as it would be if any other sublever were actuated. Obviously it would be movable through a shorter distance by the side levers than it would be by any of the others if it made contact with all the levers at the same distance from the horizontal plane containing their common axis, because points on the side levers have less motion than a point equally distant from the axis on any of the other levers has. The means described for equalizing the movements imparted to the bar by the sublevers would be operative if the bar were not held normally in contact with the levers, so if it were desirable to provide for lost motion between the sublevers and the universal bar that might easily be done by so adjusting the mechanism that there would be a space between the levers and bar when they were in their normal positions; but in this case, as well as in the other, the bar would be movable through a certain distance by whatever lever it might be actuated. With the backward movement of the universal bar by one of the sublevers the lower end of the arm 50 is forced backward, and the dog-rocker carries the yielding dog out of and the fast dog into engagement with the escapement-wheel, and when the sublever returns to its normal position the spring 57 restores the dog-rocker, arm 50, rod 49, and the universal bar to their normal positions, and the carriage is advanced a single letter-space by its driving mechanism. Since the universal bar acts on all the sublevers to the same extent and during equal intervals when it is restored to its normal position by the spring 57, it is easy to so adjust the connection between the dog-rocker and universal

bar as to regularly secure a feed movement of the carriage whenever any type-bar has traveled a certain distance from the platen.

Various changes may be made in the mechanism above described without avoiding the spirit of the invention.

What I claim as new, and desire to secure by Letters Patent, is—

1. In a type-writing machine, the combination of a set of front-strike pivoted type-bars supported at elevations progressively increasing from the middle to the sides of the set, a system of links pivoted at their front ends to the type-bars and extending backward therefrom, a system of levers to which the rear ends of the links are pivoted, said levers extending downward from the links to and below a fixed support on which the levers are fulcrumed above their lower ends, and said system of levers being broader at the bottom than is said system of links, and key-actuated means operative on the levers at their lower ends.

2. In a type-writing machine, the combination of a system of front-strike pivoted type-bars supported at elevations progressively increasing from the middle to the sides of the set, a system of links pivoted at their front ends to the type-bars and extending backward therefrom, a system of sublevers to which the rear ends of the links are pivoted, said sublevers extending downward from the links to and below a fixed support on which the sublevers are fulcrumed above their lower ends, and said system of sublevers being broader at the bottom than is said system of links, a system of key-levers equal in width to said system of sublevers at the bottom, and connections between the key-levers and the lower ends of the sublevers.

3. In a type-writing machine, the combination of a set of front-strike pivoted type-bars, a system of levers fulcrumed between their ends on a fixed horizontal support and extending normally upward and downward therefrom, the lower ends of the levers being at different distances from said horizontal support, links connecting the upper ends of the levers with the type-bars, and key-actuated devices connected with the lower ends of the levers and operative to move them on arcs whose chords are more nearly horizontal than vertical.

4. In a type-writing machine, the combination of a set of front-strike pivoted type-bars, a system of levers fulcrumed between their ends on a fixed horizontal support and extending normally upward and downward therefrom, the upper ends of said levers being behind the type-bars and their lower ends being at different distances from said horizontal support, links connecting the upper ends of the levers with the type-bars, and key-actuated devices connected with the lower ends of the levers and operative to move them on arcs

whose chords are more nearly horizontal than vertical.

5. In a type-writing machine, the combination of a set of front-strike pivoted type-bars, a system of links pivoted to the type-bars, a system of levers fulcrumed on a fixed support and extending upward therefrom and being pivotally connected at their upper ends with said links, the lower ends of the levers and the common pivots of the levers and links being at distances from said fixed support which progressively increase from the middle to the sides of the system of levers, and key-actuated means operative on the levers at their lower ends.

6. In a type-writing machine, the combination of a set of front-strike pivoted type-bars, a system of links pivoted at their front ends to the type-bars and extending backward therefrom, a system of levers to which the rear ends of the links are pivoted, said levers extending downward from the links to a fixed support on which the levers are fulcrumed, the lower ends of said levers and the common pivots of the levers and links being at distances from said fixed support which progressively increase from the middle to the sides of the system of levers, and key-actuated means operative on the levers at their lower ends.

7. In a type-writing machine, the combination of a set of front-strike pivoted type-bars, a system of links pivoted at their front ends to the type-bars and extending backward therefrom, a system of levers to which the rear ends of the links are pivoted, said levers extending downward from the links to and below a fixed support on which the levers are fulcrumed above their lower ends, and said levers diverging from one another below the links, and key-actuated devices operative on the levers at their lower ends.

8. In a type-writing machine, the combination of a set of front-strike pivoted type-bars, a system of levers conforming at their ends to arcs which diverge from each other from the middle to the sides of the system, means connecting the levers with the type-bars, and key-actuated devices connected with the levers.

9. In a type-writing machine, the combination of a set of front-strike pivoted type-bars, a system of levers conforming at their ends to arcs which diverge from each other from the middle to the sides of the system, means connecting the levers with the type-bars, a set of key-actuated devices, and links pivoted to said key-actuated devices and to said levers.

10. In a type-writing machine, the combination of a set of front-strike pivoted type-bars, a set of key-levers, a system of sublevers conforming at their ends to arcs which diverge from each other from the middle to the sides of the system, means connecting the sublevers with the type-bars, and means connecting the sublevers with the key-levers.

11. In a type-writing machine, the combi-

nation of a set of front-strike pivoted type-bars, a set of key-levers, a system of sublevers conforming at their ends to arcs which diverge from each other from the middle to the sides of the system, means connecting the sublevers with the type-bars, and links pivoted to the sublevers and to the key-levers.

12. In a type-writing machine, the combination of a set of front-strike pivoted type-bars, a system of levers mounted on a common horizontal axis and conforming at their ends to arcs which diverge from each other from the middle to the sides of the system, means connecting the levers with the type-bars, and key-actuated devices connected with the levers.

13. In a type-writing machine, the combination of a set of front-strike pivoted type-bars, a set of key-levers, a system of sublevers mounted on a common horizontal axis and conforming at their ends to arcs which diverge from each other from the middle to the sides of the system, means connecting the sublevers with the type-bars, and means connecting the sublevers with the key-levers.

14. In a type-writing machine, the combination of a set of front-strike pivoted type-bars, a set of key-levers, a system of sublevers mounted on a common horizontal axis and conforming at their ends to arcs which diverge from each other from the middle to the sides of the system, links pivoted to the sublevers and to the type-bars, and links pivoted to the sublevers and to the key-levers.

15. In a type-writing machine, the combination of a set of front-strike pivoted type-bars, a set of key-actuated devices, a system of levers mounted on a common horizontal axis and increasing in length from the middle to the sides of the system, each lever having its ends on opposite sides of and equally distant from a plane that contains said axis and forms right angles with one of the arms of the lever, means connecting the ends of the levers on one side of their axis with the type-bars, and means connecting the other ends of the levers with the key-actuated devices.

16. In a type-writing machine, the combination of a set of front-strike pivoted type-bars, a set of key-levers, a system of sublevers mounted on a common horizontal axis and increasing in length from the middle to the sides of the system, each sublever having its ends on opposite sides of and equally distant from a plane that contains said axis and forms right angles with one of the arms of the sublever, means connecting the ends of the sublevers on one side of their axis with the type-bars, and means connecting the other ends of the sublevers with the key-levers.

17. In a type-writing machine, the combination of a set of front-strike pivoted type-bars, a set of key-levers, a system of sublevers mounted on a common horizontal axis and increasing in length from the middle to the sides of the system, each sublever having

its ends on opposite sides of and equally distant from a plane that contains said axis and forms right angles with one of the arms of the sublevers, links pivoted to the ends of the 5 sublevers on one side of their axis and to the type-bars, and links pivoted to the other ends of the sublevers and to the key-levers.

18. In a type-writing machine, the combination of a set of front-strike pivoted type-bars, a set of key-actuated devices, a system of levers having upper and lower arms and conforming at their ends to arcs which diverge from each other from the middle to the 10 sides of the system, means connecting the upper arms of the levers with the type-bars, and means connecting the lower arms with the key-actuated devices.

19. In a type-writing machine, the combination of a set of front-strike pivoted type-bars, a set of key-levers, a system of sublevers having upper and lower arms and conforming at their ends to arcs which diverge from each other from the middle to the sides of the system, means connecting the upper 15 arms of the sublevers with the type-bars, and means connecting their lower arms with the key-levers.

20. In a type-writing machine, the combination of a set of front-strike pivoted type-bars, a set of key-levers, a system of sublevers having upper and lower arms and conforming at their ends to arcs which diverge from each other from the middle to the sides of the system, links pivoted to the upper arms 20 of the sublevers and to the type-bars, and links pivoted to the lower arms of the sublevers and to the key-levers.

21. In a type-writing machine, the combination of a set of front-strike pivoted type-bars, a set of key-actuated devices, a system of levers mounted on a common horizontal axis and having upper and lower arms and conforming at their ends to arcs which diverge from each other from the middle to the 25 sides of the system, means connecting the upper arms of the levers with the type-bars, and means connecting their lower arms with the key-actuated devices.

22. In a type-writing machine, the combination of a set of front-strike pivoted type-bars, a set of key-levers, a system of sublevers mounted on a common horizontal axis and having upper and lower arms and conforming at their ends to arcs which diverge 30 from each other from the middle to the sides of the system, means connecting the upper arms of the sublevers with the type-bars, and means connecting their lower arms with the key-levers.

23. In a type-writing machine, the combination of a set of front-strike pivoted type-bars, a set of key-levers, a system of sublevers mounted on a common horizontal axis and having upper and lower arms and 35 conforming at their ends to arcs which diverge from each other from the middle to the sides of the system, means connecting the upper arms of the sublevers with the type-bars, and means connecting their lower arms with the key-levers.

24. In a type-writing machine, the combination of a set of front-strike pivoted type-bars, a set of key-actuated devices, a system of levers having upper and lower arms and conforming at their ends to arcs which diverge 40 from each other from the middle to the sides of the system, the upper arms of said levers extending behind the type-bars, means connecting the upper arms of the levers with the type-bars, and means connecting their lower arms with the key-actuated devices.

from each other from the middle to the sides of the system, links pivoted to the upper arms of the sublevers and to the type-bars, and links pivoted to their lower arms and to the key-levers.

25. In a type-writing machine, the combination of a set of front-strike pivoted type-bars, a set of key-levers, a system of sublevers having upper and lower arms and conforming at their ends to arcs which diverge from each other from the middle to the sides of the system, the upper arms of said sublevers extending behind the type-bars, means connecting the upper arms of the sublevers with the type-bars, and means connecting their lower arms with the key-actuated devices.

26. In a type-writing machine, the combination of a set of front-strike pivoted type-bars, a set of key-levers, a system of sublevers having upper and lower arms and conforming at their ends to arcs which diverge from each other from the middle to the sides of the system, the upper arms of said sublevers extending behind the type-bars, links pivoted to the upper arms of the sublevers and to the type-bars, and links pivoted to their lower arms and to the key-levers.

27. In a type-writing machine, the combination of a set of segmentally-arranged type-bars having an upward and rearward action, a set of levers mounted on supports in the front part of the base of the machine, a system of sublevers behind the others, said sublevers being movable at their ends on arcs whose chords are substantially horizontal, links connecting the upper arms of the sublevers with the type-bars, and links extending backward from the levers in the base and connected at their front ends to these levers 105 and at their rear ends to the sublevers.

28. In a type-writing machine, the combination of a set of segmentally-arranged pivoted type-bars having an upward and rearward action, a set of key-actuated devices in 110 the front part of the base of the machine, a system of levers extending below, and above and behind, the pivoted ends of the type-bars, said levers being movable at their ends on arcs whose chords are substantially horizontal, means connecting the levers with the type-bars, and links extending under the type-bars from the key-actuated devices to the levers.

29. In a type-writing machine, the combination of a set of front-strike pivoted type-bars, a set of key-levers, a system of sublevers having upper and lower arms and conforming at their ends to arcs which diverge 115 from each other from the middle to the sides of the system, the upper arms of said sublevers extending behind the type-bars, means connecting the upper arms of the sublevers with the type-bars, and means connecting their lower arms with the key-actuated devices.

nation of a set of front-strike pivoted type-bars, a set of key-actuated devices in the front part of the base of the machine, a system of levers behind the key-actuated devices, these 5 levers having upper and lower arms and conforming at their ends to arcs which diverge from each other from the middle to the sides of the system, means connecting the upper arms of the levers with the type-bars, and connections extending from the key-actuated devices backward to the lower arms of the levers.

30. In a type-writing machine, the combination of a set of front-strike pivoted type-bars, a set of levers mounted on supports in 15 the front part of the base of the machine, a system of sublevers behind the others, the sublevers having upper and lower arms and conforming at their ends to arcs which diverge from each other from the middle to the sides 20 of the system, means connecting the upper arms of the sublevers with the type-bars, and connections extending from the levers in the base backward to the lower arms of the sublevers.

25. 31. In a type-writing machine, the combination of a set of front-strike pivoted type-bars, a set of levers mounted on supports in the front part of the base of the machine, a system of sublevers behind the others, the sublevers having upper and lower arms and conforming at their ends to arcs which diverge from each other from the middle to the sides 30 of the system, links pivoted to the upper arms of the sublevers and to the type-bars, and links extending backward from the levers in the base and pivoted at their front ends to these levers and at their rear ends to the lower arms of the sublevers.

32. In a type-writing machine, the combination of a set of front-strike pivoted type-bars, a set of key-actuated devices in the front part of the base of the machine, a system of levers behind the type-bars, these levers having upper and lower arms and conforming at 45 their ends to arcs which diverge from each other from the middle to the sides of the system, means connecting the upper arms of the levers with the type-bars, and links extending under the type-bars from the key-actuated devices to the lower arms of the levers.

33. In a type-writing machine, the combination of a set of front-strike pivoted type-bars, a set of levers mounted on supports in the front part of the base of the machine, a system of sublevers mounted on a common horizontal axis and having upper and lower arms and conforming at their ends to arcs which diverge from each other from the middle to the sides of the system, the upper arms 55 of said sublevers extending behind the type-bars, means connecting the upper arms of the sublevers with the type-bars, and connections extending from the levers in the base backward to the lower arms of the sublevers.

60. 34. In a type-writing machine, the combi-

nation of a set of front-strike pivoted type-bars, a set of levers mounted on supports in the front part of the base of the machine, a system of sublevers mounted on a common horizontal axis and having upper and lower 70 arms and conforming at their ends to arcs which diverge from each other from the middle to the sides of the system, the upper arms of said sublevers extending behind the type-bars, means connecting the upper arms of the 75 sublevers with the type-bars, and links extending backward from the levers in the base and pivoted at their front ends to these levers and at their rear ends to the lower arms of the sublevers.

35. In a type-writing machine, the combination of a set of front-strike pivoted type-bars, a system of sublevers having upper and lower arms, means connecting the upper arms of the sublevers with the type-bars, a set of 85 key-levers mounted on cross-rods in the front portion of the base of the machine, one arm of each key-lever extending backward and downward and the other backward and upward from the supporting-rod when the key-lever is in its normal position, finger-keys operatively connected with the key-levers, and links pivoted to the key-levers near their lower ends and to the lower arms of the sublevers.

36. In a type-writing machine, the combination of a set of front-strike pivoted type-bars, a system of sublevers having upper and lower arms and conforming at their ends to arcs that diverge from each other from the middle to the sides of the system, means connecting the upper arms of the sublevers with the type-bars, a set of key-levers mounted on cross-rods in the front portion of the base of the machine, one arm of each key-lever extending backward and downward and the other 95 backward and upward from the supporting-rod when the key-lever is in its normal position, finger-keys operatively connected with the key-levers, and links pivoted to the key-levers near their lower ends and to the lower 100 arms of the sublevers.

37. In a type-writing machine, the combination of cross-rods in the front of the base of the machine, the ends of said rods being between the sides of the base, key-actuated 115 mechanism supported by said rods, and rod-holding devices securing the rods in the base and comprising parts which are movable to release the rods.

38. In a type-writing machine, the combination of cross-rods in the front part of the base of the machine, the ends of the rods being between the sides of the base, key-actuated mechanism supported by said rods, and rod-clamps fixed to the frame and engaging 120 the rods within the base.

39. In a type-writing machine, the combination of cross-rods in the front part of the base of the machine, key-actuated mechanism supported by said rods, and rod-clamps com- 125 130

rising recessed blocks on the frame, screws in the blocks, and movable jaws operative by the screws within the recesses in the blocks.

40. In a type-writing machine, the combination of a set of front-strike pivoted type-bars, a set of key-actuated devices, a system of levers having upper and lower arms and conforming at their ends to arcs which diverge from each other from the middle to the sides of the system, the radius of the arc to which the lower ends of the levers conform being longer than that of the other arc, means connecting the upper arms of the levers with the type-bars, and means connecting their lower arms with the key-actuated devices.

41. In a type-writing machine, the combination of a set of front-strike pivoted type-bars, a set of key-levers, a system of sublevers having upper and lower arms and conforming at their ends to arcs which diverge from each other from the middle to the sides of the system, the radius of the arc to which the lower ends of the sublevers conform being longer than that of the other arc, means connecting the upper arms of the sublevers with the type-bars, and means connecting their lower arms with the key-levers.

42. In a type-writing machine, the combination of a set of front-strike pivoted type-bars, a set of key-levers, a system of sublevers having upper and lower arms and conforming at their ends to arcs which diverge from each other from the middle to the sides of the system, the radius of the arc to which the lower ends of the sublevers conform being longer than that of the other arc, links pivoted to the upper arms of the sublevers and to the type-bars, and links pivoted to their lower arms and to the key-levers.

43. In a type-writing machine, the combination of a set of front-strike type-bars, a set of key-actuated devices, a system of levers having upper and lower arms and conforming at their ends to arcs which diverge from each other from the middle to the sides of the system, said system being wider at the lower ends of the levers than it is at their upper ends, means connecting the upper arms of the levers with the type-bars, and means connecting their lower arms with the key-actuated devices.

44. In a type-writing machine, the combination of a set of front-strike pivoted type-bars, a set of key-levers, a system of sublevers having upper and lower arms and conforming at their ends to arcs which diverge from each other from the middle to the sides of the system, said system being wider at the lower ends of the sublevers than it is at their upper ends, means connecting the upper arms of the sublevers with the type-bars, and means connecting their lower arms with the key-levers.

45. In a front-strike type-writing machine comprising a set of segmentally - arranged

type-bars, a system of key-actuated sublevers, and connecting devices between the sublevers and type-bars, the relations of said parts rendering the sublevers operative to move said connecting devices in substantially horizontal directions, the combination with said sublevers of a universal bar subject to contact with the sublevers at different elevations from side to side of the system and operative by each of said sublevers to actuate the carriage - feed mechanism.

46. In a front-strike type-writing machine comprising a set of segmentally - arranged type-bars, a system of key-actuated sublevers, and connecting devices between the sublevers and type-bars, the relations of said parts rendering the sublevers operative to move said connecting devices in substantially horizontal directions, the combination with said sublevers of a horizontally-movable universal bar supported by parallel guides, said bar being subject to contact with the sublevers from side to side of the system and operative by each of said sublevers to actuate the carriage - feed mechanism.

47. In a front-strike type-writing machine comprising a set of segmentally - arranged type-bars, a system of key-actuated sublevers, and connecting devices between the sublevers and type-bars, the relations of said parts rendering the sublevers operative to move said connecting devices in substantially horizontal directions, the combination with said sublevers of a universal bar subject to contact with the sublevers above their pivots from side to side of the system and operative by each of said sublevers to actuate the carriage - feed mechanism.

48. In a front-strike type-writing machine, the combination of a system of sublevers extending behind and connected with the type-bars, key-actuated mechanism connected with the sublevers, and a universal bar secured behind the sublevers and being in contact with the backs of the sublevers at different elevations when these and the bar are in their normal positions, and being operative by each sublever to actuate the carriage - feed mechanism.

49. In a type-writing machine, the combination of a system of levers whose movements are measured by angles decreasing in size from the middle to the sides of the system, and a universal bar movable by the levers to actuate the carriage - feed mechanism, said combination including means to equalize the movements imparted to the bar by means of the levers.

50. In a type-writing machine, the combination of a system of key-actuated levers whose movements are measured by different angles, and carriage - feed mechanism on which each lever acts from the beginning to the end of the movement imparted to the lever by the depression of its key, said combination including means to equalize the movements im-

parted by means of the levers to a portion of the carriage-feed mechanism.

51. In a type-writing machine, the combination of a system of key-actuated levers whose movements are measured by different angles, and carriage-feed mechanism comprising a universal bar on which each lever acts from the beginning to the end of the movement imparted to the lever by the depression of its key, said combination including means to equalize the movements imparted by the levers to the universal bar.

52. In a type-writing machine, the combination of a system of levers whose movements are measured by angles decreasing in size from the middle to the sides of the system, and a universal bar operative by the levers to actuate the carriage-feed mechanism, that face of the bar on which the levers act being composed of surfaces forming an obtuse angle and arranged to secure the proper relations between the bar and the levers.

53. In a type-writing machine, the combination of a system of levers whose movements are measured by different angles, and a universal bar operative by each lever acting immediately on the bar to actuate the carriage-feed mechanism, that face of the bar on which the levers act being composed of surfaces forming an obtuse angle and arranged to fit the bar to the levers and subject it to contact with those portions of the levers by which the bar is movable through a certain distance.

54. In a type-writing machine, the combination of a system of sublevers whose movements are measured by angles decreasing in size from the middle to the sides of the system, these sublevers extending behind and being connected with the type-bars, key-actuated mechanism connected with the sublevers, and a universal bar secured behind the sublevers and movable by each sublever toward the back of the machine to actuate the carriage-feed mechanism, the front face of the bar or that on which the sublevers act being composed of surfaces forming an obtuse angle and arranged to secure the proper relations between the bar and the sublevers.

55. In a type-writing machine, the combination of a system of sublevers whose movements are measured by different angles, these sublevers extending behind and being connected with the type-bars, key-actuated mechanism connected with the sublevers, and a universal bar secured behind the sublevers and movable by each sublever toward the back of the machine to actuate the carriage-feed mechanism, the front face of the bar or that on which the sublevers act being composed of surfaces forming an obtuse angle and arranged to fit the bar to the sublevers and subject it to contact with those portions of the sublevers by which the bar is movable through a certain distance.

65 56. In a type-writing machine, the combi-

nation of a system of levers whose movements are measured by different angles, these levers being mounted on a common horizontal axis, and carriage-feed mechanism comprising a universal bar on which the levers act, the bar being bent to subject it to contact with the levers at different distances from said axis.

57. In a type-writing machine, the combination of a system of sublevers mounted on a common horizontal axis and connected with the type-bars, and having arms extending in front of and inclined at small angles to a vertical plane containing said axis when the sublevers are in their normal positions, said angles of inclination decreasing in size from the middle to the sides of the system, key-actuated mechanism connected with the sublevers, and a universal bar secured behind said arms of the sublevers and operative thereby to actuate the carriage-feed mechanism, the front face of said bar being composed of surfaces properly arranged to secure contact between the bar and the backs of the sublevers from side to side of the system.

58. In a type-writing machine, the combination of a system of sublevers mounted on a common horizontal axis and connected with the type-bars, and having arms extending in front of and inclined at small angles to a vertical plane containing said axis when the sublevers are in their normal positions, said angles of inclination decreasing in size from the middle to the sides of the system, key-actuated mechanism connected with the sublevers and operative to impart to said arms movements through different angles decreasing in size from the middle to the sides of the system, and a universal bar secured behind said arms of the sublevers and operative thereby to actuate the carriage-feed mechanism, the front face of said bar being composed of surfaces forming an obtuse angle and arranged to secure contact between the bar and the backs of said arms of the sublevers from side to side of the system, and the bar being bent to subject it to contact with said arms of the sublevers at different distances from said axis.

59. In a type-writing machine, the combination of a front-strike pivoted type-bar, a key-actuated device, a straight lever having symmetrical arms and movable at its ends on arcs whose chords are substantially horizontal, means connecting one arm of said lever with the type-bar, and means connecting its other arm with the key-actuated device.

60. In a type-writing machine, the combination of a front-strike pivoted type-bar, a key-lever, a straight sublever having symmetrical arms and movable at its ends on arcs whose chords are substantially horizontal, a link pivoted to one arm of the sublever and to the type-bar, and a link pivoted to the other arm of the sublever and to the key-lever.

61. In a type-writing machine, the combination of a set of front-strike pivoted type-

bars, a system of levers having upper and lower arms, means connecting the upper arms of said levers with the type-bars, a system of key-actuated devices in the front part of the 5 base of the machine, and a system of links pivoted at their front ends to the key-actuated devices and at their rear ends to the lower arms of said levers, the system of key-actuated devices and the system of links and the 10 system of levers at the bottom being substantially equal in width.

62. In a type-writing machine, the combination of a set of front-strike pivoted type-bars, a system of levers mounted on a common 15 horizontal axis and having upper and lower arms and conforming at their ends to arcs which diverge from each other from the middle to the sides of the system, means connecting the upper arms of said levers with the 20 type-bars, a system of key-actuated devices in the front part of the base of the machine, and a system of links pivoted at their front ends to the key-actuated devices and at their rear ends to the lower arms of said levers, the 25 system of key-actuated devices and the system of links and the system of levers at the bottom being substantially equal in width.

63. In a type-writing machine, the combination of a set of front-strike pivoted type-bars, a system of links pivoted thereto, a system 30 of levers to which the links are pivoted, said levers extending downward from the links and being fulcrumed above their lower ends on a fixed support, and the system of levers being broader at the bottom than is the system of links, and the levers being movable at 35 their lower ends on arcs whose chords are more nearly horizontal than vertical, and key-actuated means operative on the levers at their lower ends.

64. In a type-writing machine, the combination of a set of front-strike pivoted type-bars, a system of links pivoted thereto, a system 45 of sublevers to which the links are pivoted, said sublevers extending downward from the links and being fulcrumed above their lower ends on a fixed support, and the system of sublevers being broader at the bottom than is the system of links, and the sublevers being 50 movable at their lower ends on arcs whose chords are more nearly horizontal than vertical, a system of key-levers equal in width to the system of sublevers at the bottom, and connections between the key-levers and the 55 lower ends of the sublevers.

65. In a type-writing machine, the combination of a set of front-strike pivoted type-bars, a system of links pivoted thereto, a system 60 of key-levers, a system of sublevers fulcrumed between their ends on a fixed support and extending upward and downward therefrom and being pivotally connected at their upper ends with said links and movable at their lower ends on arcs whose chords are 65 more nearly horizontal than vertical, the width

of the system of sublevers at the bottom being that of the system of key-levers at the keyboard, and connections between the key-levers and the lower ends of the sublevers.

66. In a type-writing machine, the combination of a set of front-strike pivoted type-bars, a system of links pivoted thereto, a system of levers to which the links are pivoted, said levers extending downward from the links and being fulcrumed above their lower ends 75 on a fixed support, the lower arms of the levers increasing in length from the middle to the sides of the system, and the system of levers being broader at the bottom than is the system of links, and the levers being movable 80 at their lower ends on arcs whose chords are more nearly horizontal than vertical, and key-actuated means operative on the levers at their lower ends.

67. In a type-writing machine, the combination of a set of front-strike pivoted type-bars, a system of links pivoted thereto, a system of sublevers to which the links are pivoted, said sublevers extending downward from the links and being fulcrumed above their 85 lower ends on a fixed support, the lower arms of the sublevers increasing in length from the middle to the sides of the system, and the system of sublevers being broader at the bottom than is the system of links, and the sublevers 90 being movable at their lower ends on arcs whose chords are more nearly horizontal than vertical, a system of key-levers equal in width to the system of sublevers at the bottom, and connections between the key-levers and lower 95 ends of the sublevers.

68. In a type-writing machine, the combination of a set of front-strike pivoted type-bars, a system of links pivoted thereto, a system of key-levers, a system of sublevers fulcrumed between their ends on a fixed support 105 and extending upward and downward therefrom and being pivotally connected at their upper ends with said links and movable at their lower ends on arcs whose chords are 110 more nearly horizontal than vertical, the lower arms of the sublevers increasing in length from the middle to the sides of the system and the width of the system of sublevers at the bottom being that of the system of key-levers 115 at the keyboard, and connections between the key-levers and the lower ends of the sublevers.

69. In a type-writing machine, the combination of a set of front-strike pivoted type-bars, a system of links pivoted thereto, a system of levers to which the links are pivoted, said levers extending downward from the links and being fulcrumed on a fixed support, the lower arms of the levers increasing in 120 length from the middle to the sides of the system and the system of levers being broader at the bottom than is the system of links, and key-actuated means operative on the levers at 125 their lower ends.

70. In a type-writing machine, the combination of a set of front-strike pivoted type-bars, a system of links pivoted thereto, a system of sublevers to which the links are pivoted, said sublevers extending downward from the links and being fulcrumed on a fixed support, the lower arms of the sublevers increasing in length from the middle to the sides of the system and the system of sublevers being broader at the bottom than is the system of links, a system of key-levers equal in width to the system of sublevers at the bottom, and connections between the key-levers and lower ends of the sublevers.

71. In a type-writing machine, the combination of a set of front-strike pivoted type-bars, a system of links pivoted thereto, a system of key-levers, a system of sublevers fulcrumed on a fixed support and extending upward therefrom and being pivotally connected at their upper ends with said links, the lower arms of the sublevers increasing in length from the middle to the sides of the system and the width of the system of sublevers at the bottom being that of the system of key-levers at the keyboard, and connections between the key-levers and the lower ends of the sublevers.

72. In a type-writing machine, the combination of a set of front-strike pivoted type-bars, a system of links pivoted at their front ends to the type-bars and extending backward therefrom, a system of levers to which the rear ends of the links are pivoted, said levers extending downward from the links and being fulcrumed on a fixed support, the lower arms of the levers increasing in length from the middle to the sides of the system, and said system of levers being broader at the bottom than is said system of links, and key-actuated means operative on the levers at their lower ends.

73. In a type-writing machine, the combination of a set of front-strike pivoted type-bars, a system of links pivoted at their front ends to the type-bars and extending backward therefrom, a system of sublevers to which the rear ends of the links are pivoted, said sublevers extending downward from the links and being fulcrumed on a fixed support, the lower arms of the levers increasing in length from the middle to the sides of the system, and said system of sublevers being broader at the bottom than is said system of links, a system of key-levers equal in width to said system of sublevers at the bottom, and connections between the key-levers and the lower ends of the sublevers.

74. In a type-writing machine, the combination of a set of front-strike pivoted type-bars, a system of links pivoted at their front ends to the type-bars and extending backward therefrom, a system of key-levers, a system of sublevers fulcrumed on a fixed support and extending upward therefrom and being con-

nected at their upper ends to the rear ends of said links, the lower arms of the sublevers increasing in length from the middle to the sides of the system and the width of said system of sublevers at the bottom being that of the system of key-levers at the keyboard, and connections between the key-levers and lower ends of the sublevers.

75. In a type-writing machine, the combination of a set of front-strike pivoted type-bars mounted on an upwardly and downwardly movable segment, a set of levers fulcrumed on a fixed support, the ends of each lever being at different elevations, and the lower arms of the levers increasing in length from the middle to the sides of the system, means connecting the upper ends of the levers to the type-bars and operative by the levers both when the segment is in its lower position and when it is in its upper position, and key-actuated devices connected with the lower ends of said levers.

76. In a type-writing machine, the combination of a set of front-strike pivoted type-bars mounted on an upwardly and downwardly movable segment, a system of levers fulcrumed on a fixed support, the ends of each lever being at different elevations, and the lower arms of the levers increasing in length from the middle to the sides of the system, links pivoted to the type-bars and to said levers, and key-actuated devices connected with the lower ends of said levers.

77. In a type-writing machine, the combination of a set of front-strike pivoted type-bars, a system of levers fulcrumed on a fixed support, the ends of each lever being at different elevations, and the lower arms of the levers increasing in length from the middle to the sides of the system and said levers diverging from one another below their upper ends, a system of links pivoted to the type-bars and to the upper ends of said levers, and key-actuated devices operative on the lower arms of the levers.

78. In a type-writing machine, the combination of a set of front-strike pivoted type-bars, a system of levers fulcrumed on a fixed support, the ends of each lever being at different elevations, and the lower arms of the levers increasing in length from the middle to the sides of the system and said levers diverging from one another below their upper ends, a system of links pivoted to the type-bars and extending thence backward and being pivoted at their rear ends to the upper ends of said levers, and key-actuated devices operative on the lower arms of the levers.

79. In a type-writing machine, the combination of a set of front-strike pivoted type-bars, a system of levers fulcrumed on a fixed support, the ends of each lever being at different elevations, and the lower arms of the levers increasing in length from the middle to the sides of the system, and said levers di-

verging from one another below their upper ends, and being movable at their lower ends on arcs whose chords are more nearly horizontal than vertical, a system of links pivoted to the type-bars and to the upper ends of said levers, and key-actuated devices operative on the lower arms of the levers.

80. In a type-writing machine, the combination of a set of front-strike pivoted type-bars, a system of levers fulcrumed on a fixed support, the ends of each lever being at different elevations and the lower arms of the levers increasing in length from the middle to the sides of the system, and said levers diverging from one another below their upper ends and being movable at their lower ends

on arcs whose chords are more nearly horizontal than vertical, a system of links pivoted to the type-bars and extending thence backward and being pivoted at their rear ends to the upper ends of said levers, and key-actuated devices operative on the lower arms of the levers.

Signed in the borough of Manhattan, city of New York, in the county of New York and State of New York, this 22d day of June, A. D. 1903.

JACOB FELBEL.
